W. Darker, Jr.,
Rotary Steam Engine.
No 15,371. Patented July 22, 1856.

Fig. 1.

UNITED STATES PATENT OFFICE.

WILLIAM DARKER, JR., OF WEST PHILADELPHIA, PENNSYLVANIA.

VIBRATORY STEAM-ENGINE.

Specification of Letters Patent No. 15,371, dated July 22, 1856.

To all whom it may concern:

Be it known that I, WILLIAM DARKER, Jr., of West Philadelphia, in the county of Philadelphia and State of Pennsylvania, 5 have invented a new and Improved Form of Steam-Engine; and I do hereby declare that the following is a full, clear, and exact description of the same, reference being had to the accompanying drawings, forming 10 part of this specification, in which—

Figure 1, is a side elevation of the engine, with one side of the steam box removed, to show the interior. Fig. 2, is a vertical section of the same in a plane passing 15 through the axis.

Similar letters of reference indicate corresponding parts in the two figures.

A, is what I term, an oscillating piston, consisting of a metal roller of the form of 20 a cylinder which has a cavity a, a' , extending from end to end and from the periphery nearly to the center, said cavity being of sector shape and being equal to not less than one fourth of the cylinder. This piston may 25 be solid or hollow, but, if hollow, must be entirely closed up; it has its peripherical surface turned up truly and its ends faced up square with the axis, and has the bottom b , of the cavity a, a' faced concentri- 30 cally to the axis. The piston, thus constructed, is provided, at its ends, with journals c, c' , which are received in proper bearings in the parallel ends d, d' , of a closed square box B, which I term the steam 35 box. This steam box may be, in its section taken perpendicularly to the axis of the oscillating piston A, either of quadrangular form as shown in Fig. 1, or may have an arched bottom to fit nearly close to the 40 peripherical of the oscillating piston. One or both of the ends d, d' , of the steam box, must be movable to allow the piston to be inserted. From the top of the steam box a fixed partition e , extends downward far 45 enough to meet the bottom b , of the cavity a, a' . The bottom face of the partition e , is grooved, to receive a packing, f , of leather, hemp, metal or other material, which is intended to fit closely to the face b , so as 50 to prevent steam or water passing from the face a , to the face a' , of the cavity in the piston, which form the faces of the piston. The ends d, d' , of the steam box, are each 55 grooved to receive one of two packing pieces g, g , of metal or other material, which are

formed as shown in Fig. 1, with rings to fit around the oscillating piston and extend down to the bottom of the steam box; the said packing pieces fitting close to the parallel ends of the oscillating piston, as 60 shown in Fig. 2. The bottom of the steam box is grooved straight across to receive a straight strip h , of metallic or other packing which fits to the peripherical surface of the piston. By means of the several 65 packing pieces, which should all be backed with springs or elastic material, to keep them in contact with the piston, the division of the steam box into two steam tight chambers C, C' , is effected, and leakage around 70 the journals is prevented. The two steam chambers are intended to be fitted with water to a level above the packing f , as for instance, to j, j , Fig. 1, and each chamber is furnished with a cock k , communicating 75 with the boiler below the water line, and so governed by a float l , as to open the cock when the water gets below the requisite level, but to close it when up to the proper 80 level.

D, is a steam chest which is represented as being placed on the top of the steam box B, but which may be in any other position. This steam chest contains a slide valve like that commonly applied to a reciprocating 85 steam engine of the common kind, with a similar arrangement of parts and passages, the two passages which generally communicate with the cylinder, communicating through pipes i, i' with the steam chambers C and C' , at or near the top of said chambers. By working this slide valve over the ports, steam is admitted to each chamber alternately and allowed to exhaust from the other one, and by its pressure on the faces 90 a, a' , alternately, is caused to produce an oscillating movement of the piston, A. This oscillating motion is converted into a continuous rotary motion by providing the journals c , which protrude through the 95 steam box, with an arm E, which connects by a connecting rod F with a crank I, on the main shaft G, of the engine, which is supported in bearings on standards H, H, which may be erected on top of the steam 100 box, as shown, or on any other suitable foundation. This shaft may be provided with a fly-wheel K. The crank I must be proportionably shorter than the arm E, to allow the piston the requisite amount of 105 110

motion to bring its faces a , a' , as near as desirable to the partition e . The slide valve may be worked by an eccentric J , connected with it by a rod m , or may derive its motion 5 through any suitable arrangement of valve gear, from any convenient part of the engine.

This form of engine possesses the advantage over other forms in its extreme 10 simplicity and cheapness of construction, while leakage of steam is very effectually provided against by interposing water between the steam and all the working parts of the engine. The water also serves to 15 lubricate the working parts.

I will here remark that the cocks k , k' , are only required to supply enough water to make up for the waste by evaporation.

I do not claim the interposition of water

between the steam and the working parts 20 of a steam engine. But

What I claim as my invention and desire to secure by Letters Patent, is—

The oscillating piston A , of the form substantially herein specified, arranged 25 within a steam box B , which is provided with a partition e , and with suitable packing, all substantially as herein described, and with a suitable arrangement of a valve or valves and passages, the whole operating 30 as herein set forth, in connection with suitable means of converting the oscillating movement of the piston into a continuous rotary motion.

WILLIAM DARKER, JR.
